UNITED STATES PATENT OFFICE.

WALTER F. STOLZENBURG AND HERMAN R. LEUBNER, OF SHEBOYGAN, WISCONSIN.

DESIGN FOR A GRILL FOR TALKING-MACHINE CABINETS.

55,726.

Specification for Design.

Patented July 6, 1920.

Application filed April 26, 1920. Serial No. 376,876. Term of patent 14 years.

To all whom it may concern:

Be it known that we, WALTER F. STOLZENBURG, a citizen of United States, and HERMAN R. LEUBNER, a citizen of United States, residing at Sheboygan, in the county of Sheboygan and State of Wisconsin, have invented a new, original, and ornamental Design for Grills for Talking-Machine Cabinets, of which the following is a specification, reference being had to the accompanying drawing, forming part thereof.

The figure is a perspective view of a grill for talking machine cabinets, showing our new design.

We claim:

The ornamental design for a grill for talking machine cabinets as shown.

WALTER F. STOLZENBURG.
HERMAN R. LEUBNER.
